ABSTRACT

A carburetor for an internal combustion engine utilizes a rotatable air motor to achieve intimate mixing of fuel and air and hence provide a combustible mixture of enhanced burning qualities to the engine. The air motor utilizes a hollow, rotatable hub with fuel jets to deliver the fuel and a plurality of vanes to atomize the same. The air motor is driven by the flow of air through the air horn except when airflow is minimal (closed or nearly closed throttle positions). During this minimal airflow, the engine creates a suction head which is utilized to cause air to flow over a turbine that is coupled with the air motor, thereby rotating the turbine to, in turn, drive the motor. During deceleration, fuel is not required to be supplied to the engine and hence mechanism is provided to block the flow of fuel to the engine in response to closing of the engine throttle valve. The mechanism is also operable by the decrease in pressure caused by the suction head created when the engine descends a long steep grade and hence will continue to block the flow of fuel during such a descent as long as the throttle valve remains closed.

Fuel is delivered to the air motor as a result of a suction conduit which has an outlet into the interior of the air horn. Thus, during the minimal airflow this fuel is atomized effectively by the rotation of the air motor and when fuel is not needed, the flow is completely shut off. When it is desirable to increase the quantity of fuel delivered to the air motor to meet the power requirements of the engine, one or more venturi boost rings are employed in the vicinity of the suction conduit outlet to increase the suction and hence the quantity of fuel delivered to the air motor.

CARBURETOR HAVING AUXILIARY TURBINE AND IDLE FUEL SHUTOFF MECHANISM

This invention relates to carburetors for internal combustion engines and, more particularly, to an improvement in a carburetor of the type shown and described in U.S. Pat. No. 2,668,698, entitled "Carburetor", which issued to the present applicant on Feb. 9, 1954.

Achieving proper mixture of fuel and air to provide the most highly combustible mixture is extremely important in all internal combustion engines. A significant advance in the art is represented by the above-referenced prior patent of the present applicant. A limitation of the carburetor of this prior patent however, is its inability to supply fuel to an engine in the relatively wide range of quantities required for modern high-performance engines. It has, in fact, been a limitation of prior carburetors in general that they do not have the wide range of fuel delivery capacity required by modern automobile engines. This has necessitated the use of multistage carburetors which are relatively expensive and complex, both in their initial cost and to maintain.

Another deficiency of prior art carburetors is their tendency to over-supply engines with fuel. This results in only partial combustion of the fuel with a certain percentage of the same being discharged through the engine exhaust as either partially burned or raw fuel. This is a major factor in the atmosphere pollution which is attributed to automobile engines. The over supply of fuel occurs primarily during deceleration when the engine actually requires no fuel, but the same is still supplied by the carburetor. Prior mechanical devices for keeping the engine running at a high enough speed to burn some of the excess fuel are undesirable because they sustain the engine at an undesired increased speed and also because they do not reach the source of the problem.

It is, therefore, an important object of the present invention to provide a carburetor utilizing an air motor to atomize and distribute fuel wherein relatively large motor bearings can be utilized, thus permitting the fuel passage through the motor to be enlarged and thereby increase the overall capacity of the carburetor.

As a corollary to the foregoing object it is an aim of the present invention to provide a carburetor with an increased fuel capacity thereby eliminating the need for relatively complex multistage carburetors.

A further object of the invention is to provide a carburetor with an increased fuel capacity which provides equal flow distribution between adjacent air passages of a two barrel carburetor, thereby allowing the two barrels to be fed from a single fuel metering and discharge device.

Another object of the present invention is to provide a carburetor wherein an air motor atomizes the fuel and means is provided for rotating the air motor at an increased speed to thereby achieve superior atomization of the fuel and hence, a more combustible mixture resulting in more efficient and more economical engine operation.

Yet another object of the invention is to provide a carburetor as described in the foregoing object whereby the auxiliary means employed to rotate the air motor at increased speeds is particularly effective at low engine loads when the passage of air through the carburetor is reduced and thus the speed of the rotation of the air motor would normally be reduced.

As a corollary to the foregoing object, the present invention has as an aim the provision of turbine means for rotating the air motor, and wherein the turbine is caused to rotate by the flow of air past the turbine as a result of the increased suction head present in the engine during low engine loads.

Another aim of the invention is to provide a boost venturi in combination with a carburetor as described in the foregoing objects to deliver fuel to the carburetor in larger quantities and thereby utilize the latter's increased capacity.

Another object of the present invention is to provide for an auxiliary air supply to the engine when the throttle is completely closed, thus resulting in more complete fuel consumption and eliminating the gum and deposits which would otherwise tend to build up in the throat of the carburetor.

A very important object of the invention is also to provide mechanism for blocking the flow of idle fuel to the engine when fuel is not required during deceleration, thus avoiding the discharge of unburned and partially burned fuel from the engine exhaust.

A further object of the invention is to provide idle fuel shutoff means which is responsive to both the initial throttle closing and the suction head of the engine created during long grade descents to assure that the flow of fuel will be blocked as long as the throttle valve remains closed.

An aim of the invention is also to provide mechanism for blocking the flow of fuel to the engine when fuel is not required during deceleration and thereby assuring a smooth transition from open throttle to curb idle by avoiding overloading the engine with fuel.

As a corollary to the above object, an aim of the invention is to provide mechanism for controlling the fuel flow to the engine from open throttle to engine idle which eliminates prior dashpot controls and does not require the engine to be sustained by mechanical devices at higher than desired speeds.

In the drawings:

FIG. 1 is a cross-sectional view through the fuel compartment and the air horn of a carburetor constructed according to the teachings of the present invention with portions of the air motor having been removed for purposes of illustration;

FIG. 2 is an enlarged, cross-sectional view through the air horn of the carburetor and the air motor partially visible in FIG. 1 showing details of construction of the latter;

FIG. 3 is a cross-sectional view on a reduced scale taken along line 3-3 of FIG. 2;

FIG. 4 is a partial vertical cross-sectional view similar to FIG. 2 and illustrating an alternative form of the invention wherein a plurality of venturi boost rings are employed to fully utilize the increased fuel capacity of the carburetor;

FIG. 5 is a horizontal, cross-sectional view through the walls of the carburetor housing taken immediately above the bolt and nut visible in FIG. 4 with the impact tube visible in FIG. 4 being removed for purposes of illustration;

FIG. 6 is a horizontal, cross-sectional view illustrating an alternative form for the air passage in which the air motor is disposed; and

FIG. 7 is a bottom plan view of the passage-defining housing illustrated in FIG. 6.

The present invention is best understood with reference to my above-mentioned patent and the same is incorporated herein by reference to the extent necessary to obtain a complete and full understanding of the present invention.

Referring initially to FIG. 2 of the drawings, an annular housing 10 presents an air horn which defines a central air passage 12. The walls of the housing 10 converge at 14 to provide a venturi constriction 16 intermediate the ends of the air horn. An air motor, designated generally by the numeral 18, is mounted within the venturi constriction 16 by structure which includes an upper boss 20 secured to the housing 10 by radially extending fins 22 and 24, and a lower boss 26 secured to the housing 10 by a fin 28. A support member 30 positions a bearing housing 32 in a central position within the lower boss 26. A second bearing housing 34 is held in position within the upper boss 20 by a cage 36 and a vertical support which includes a bolt 38, a coil spring 40 and a nut 42. An O-ring seal 44 is held by the cage 36 for purposes to be made clear hereinafter. A plurality of bearings 46 and 48 are disposed within the upper and lower bearing housings 34 and 32 respectively, and rotatably support the air motor 18.

The air motor 18 includes a central, hollow, rotatable axle 50 which supports a hollow, rotatable hub 52 having a plurality of vanes 54, and a pair of opposed fuel jets 56 extending therefrom. The disposition of the vanes 54 relative to the fuel jets 56 is best illustrated in FIG. 2. An extension of the hollow axle 50 mounts a turbine comprising a second rotatably hub 58 and a plurality of vanes 60 upwardly from the air motor 18 in spaced relationship to the latter. A baffle 62 is disposed within the hollow axle 50 to direct fuel outwardly toward the fuel jets 56. A fuel passage is presented by an extension 64 of

the support member 30 and a bore 66 within the fin 28, the bore 66 communicating directly with the fuel compartment 67 (FIG. 1). An opening 68 in the lower boss 26 presents a fuel well which is in direct communication with the fuel passage as a result of a plurality of openings in the extension 64.

An impact tube (not shown) directs air into a passage 70 which communicates with the fuel compartment and air from the passage 70 is directed into the aforementioned fuel passage through a conduit 72. As explained in the above-referenced patent, a piston 74, coupled with an actuating rod 76, operates a needle valve (not shown) for controlling the flow of fuel into the bore 66 during maximum engine power requirements. An air passage 78 communicates the area of the housing 10 within which the piston 74 is disposed with the suction head created by the engine by virtue of the outlet port 80 which opens into the interior of the air horn below an engine throttle valve 81 (FIG. 1). The air passage 78 communicates with the turbine presented by hub 58 and vanes 60 as a result of passages 82 and 84 in the housing 10 and the fin 24 respectively. Thus, the turbine means is also under the control of the suction head of the engine as a result of the aforementioned passages. Control means in the nature of a screw valve 86 is selectively positionable within the juncture of passages 82 and 84 to control the airflow through the passages. A keeper spring 88 maintains a given setting of the screw valve 86.

An impact tube 90 in the wall of the housing 10 opposite the passage 70 directs air via a passage 92 to an auxiliary fuel jet 94. The fuel jet 94 receives fuel during sudden acceleration as a result of a series of valves (not shown) operable by the throttle control mechanism as explained in the referenced patent.

An opening 96 in the boss 20 communicates with appropriate openings in the lower end of bolt 38 and the hollow axle 50 to present a suction conduit in communication with the fuel passage presented by extension 64 and bore 66. This suction conduit has an outlet port 98 which is directly opposite an outlet port 100 for a second suction conduit presented by passages 102 and 104 in the housing 10 and the fin 22 respectively. This second suction conduit communicates with the first suction conduit and, therefore, likewise with the fuel passage. Third and fourth suction conduits identical to the two mentioned above, but 180° removed therefrom, are also normally provided in communication with the fuel passage, but these have been omitted from FIG. 1 for clarity. Opening 96' and passage 102' which form a part of the third and fourth suction conduits are, however, visible in FIG. 3.

Referring now to FIG. 1, the fuel compartment 67 presents a fuel storage area 110 into which fuel is introduced through a connection 112. The introduction of fuel into the area 110 is controlled by a valve 114 which is actuated by a float 116. The fuel compartment housing 67 also defines a chamber 118 which communicates with the fuel storage area 110 through an interconnecting passage 120. The passage 120 is provided with a first ball check valve 122 which permits the flow of fuel into the passage 120 through inlet passage 124 while blocking the flow of fuel in the opposite direction, and a second ball check valve 126 which is biased by a coil spring 128 to present a restricted outlet into the fuel storage area through an outlet port 130. A portion of the passage 120 is presented by a yieldable member in the form of a flexible diaphragm 132 for purposes to be made clear hereinafter.

A plunger mechanism 134 is coupled with the throttle valve 81 through a connecting rod 136, an operating rod 138, and an arm 140 which is an integral part of the rod 138. The plunger mechanism 134 includes a flexible plunger cup 142 which is mounted at the base of an upstanding stem 144, the latter being surrounded by a coil spring 146. The arm 140 is slidably received on the stem 144 and is biased away from the plunger cup 142 by the spring 146.

As explained above, fuel is delivered to the air motor 18 through the bore 66 which communicates the fuel storage area 110 through an orifice body 148 and a connecting passage 150. The orifice body 148 and the passage 150 comprise part

of a fuel delivery conduit 152 which extends through an orifice-defining seat 154. As explained in the referenced patent, fuel is delivered through the conduit 152, a second conduit 156, and an interconnecting passage 158 to discharge ports 160 and 162 during idle operation of the engine. The discharge port 160 is just below the edge of the throttle valve 81 when the latter is in a closed position, and the flow of fuel to the engine under these circumstances is determined by the needle valve 164 which is held by a spring 166.

A pressure responsive structure is disposed for blocking the flow of fuel in the conduit 152 and the fuel delivery bore 66 when the throttle valve 81 is closed and the engine is operating at a sufficiently high speed to cause a suction head of relatively large magnitude. This structure includes a yieldable actuator member in the form of a flexible diaphragm 168 which cooperates with a second diaphragm 170 to define a pressure chamber therebetween. The pressure chamber is communicated with the suction head of the engine by a branch 172 of the air passage 78. Yielding of the diaphragm 168 operates a valve member which includes an actuating rod 174 coupled with the diaphragm 168 and a needle valve 176 which is supported by the diaphragm 132. A coil spring 178 maintains the valve 176 in an open position and a coil spring 180 likewise maintains the actuating rod 174 in a raised position. A passageway 182 communicates the area beneath the diaphragm 170 with the area 110 for purposes to be made clear hereinafter. It will be appreciated that the rod 174 is slidably received by an opening in the adjacent housing to permit the rod to engage the needle valve 176.

A shoulder 184 on the stem of the needle valve 176 provides a retainer for a second valve in the form of a closure plate 186 which is slidably received by the stem of the valve 176. A coil spring 188 biases the closure plate 186 against the shoulder 184 which limits movement of the plate 186 in one direction.

It is, of course, to be appreciated that the suction head of the engine is minimal when the throttle valve 81 is in its wide-open position. This allows maximum flow of air through the passage 12, past the air motor 18 and into the combustion chambers of the engine. This flow of air past the air motor 18 causes the latter to rotate. The flow of air through the passage 12 also creates a suction at the outlet ports 98 and 100 which causes fuel to be drawn up through the fuel passage and distributed outwardly to the rotating fuel jets 56. The baffle 62 directs the flow of fuel radially outwardly to the jets 56. The vanes 54 atomize the fuel as the latter is introduced into the air passage in a manner which is most effective in producing a fuel mixture of a more highly combustible nature.

As the throttle valve is closed, the flow of air through the passage 12 is reduced and the suction head created by the engine during operation is of an increasingly greater magnitude. Heretofore it has been necessary to utilize a relatively small axle 50 for the air motor 18 since the bearings 46 and 48 were necessarily of a relatively small size in order to exhibit the highly frictionless qualities required to maintain operation of the air motor 18 when the flow of air through the passage 12 was reduced. This, in turn, limited the size of the fuel passage which could be utilized to deliver fuel to the hollow hub 52. The overall capacity of the carburetor is, of course, determined by the size of this fuel passage. In the present invention, bearings 46 and 48 of a larger size can be utilized, thus accommodating a larger fuel passage as a result of the turbine presented by hub 58 and vanes 60. As the suction head of the engine increases, an increasing suction is present at the outlet port 80 which communicates the auxiliary turbine with the suction head of the engine through passages 78, 82 and 84. Thus, the suction head causes airflow over the turbine rotating the latter and thus effecting rotation of the air motor 18 at an increased speed over that which would be possible in the absence of the auxiliary turbine. Not only is the air motor 18 maintained in operation when it would not otherwise be possible because of the larger, more frictional bearings 46 and 48, but the motor 18 is rotated at an increased speed thereby

achieving better atomization of the fuel introduced into the carburetor.

The suction created by the flow of air past the outlet port 98 is somewhat greater than would otherwise be the case, and thus the second suction conduit tends to equalize the different suctions at the outlet ports 98 and 100 with the effective suction acting upon the fuel passage being the average value of the suctions at the outlet ports 98 and 100. In some cases however, it may be desirable to omit the second suction conduit. The O-ring seal 44 between the suction conduit and air passages 78, 82 and 84 prevents air from being drawn past the cage 36 which would disturb the metering function of the suction conduits. Another important advantage of the present invention is the auxiliary air supply which is available during low engine loads when the flow of air through the passage 12 is reduced, as a result of the suction at the outlet port 80 which draws air over the turbine and through the passages 78, 82 and 84. It is desirable to have the vanes 60 pitched in a direction opposite the pitch of the vanes 54 to assure that the air motor will rotate in the same direction whether it is being caused to rotate by the flow of air over the turbine or past the vanes 54. This is particularly important during sudden accelerations when the suction head of the engine is momentarily increased prior to the increase in the flow of air through the passage 12. Thus, the auxiliary turbine gives the air motor an initial boost before the increased airflow can reach the vanes 54. By this arrangement, the carburetor is much more responsive to sudden accelerations. The flow of air over the auxiliary turbine is controlled by the degree to which the valve 86 extends into the air passages 82 and 84. This, in turn, controls the speed of rotation of the air motor 18 under conditions of relatively light engine loads when the suction head is causing air to flow over the turbine.

It will be appreciated that during deceleration, power is not required from the engine and it is desirable to block the flow of fuel through the idle discharge system under these circumstances. This is particularly true when a vehicle is descending a long steep grade. Thus, when an operator moves the throttle valve to a closed position, the arm 140 of the actuating rod 138 moves downwardly on the stem 144 against the action of the coil spring 146. As the plunger cup 142 is forced downwardly by the action of the coil spring 146, it forces fuel from the chamber 118 and into the passage 120. The increased pressure in the passage 120 which is magnified by the check valve 126, causes the diaphragm 132 to flex downwardly. This, in turn, moves the needle valve 176 downwardly into engagement with the seat 154 to block the flow of idle fuel into the conduit 152. The shoulder 184 is positioned relative to the end of the needle valve to cause the closure plate 186 to be unseated from the shoulder 184 when the plate 186 engages the leading edge of the orifice body 148. The plate 186 is biased into engagement with the body 148 by the coil spring 188, thereby blocking the flow of fuel to the air motor 18 through the fuel delivery bore 66. It will be appreciated that the closing of the valves 176 and 186 lags somewhat behind the closing of the throttle valve 81. That is, closing of the valve 81 first results in compression of the spring 146 which, upon subsequent expansion, causes the increased pressure in the passage 120 which, in turn, closes the valves 176 and 186. This is desirable to assure that the increased pressure in the passage 120 will be maintained for a short period after the throttle 81 is closed to thereby maintain the valves 176 and 186 closed until the engine speed has had time to slow down to match the new throttle opening. The ball check valve 126 and its associated spring 128 also facilitate maintaining an increased pressure in the passage 120 for a longer period of time than would otherwise be possible.

Once all of the fuel has been forced from the chamber 118, the pressure in the passage 120 gradually returns to normal and, were it not for the actuator rod 174, the diaphragm 132 would return to its normal position raising the valve 176 with it to again open the bore 66 and the conduit 152 to the flow of fuel. However, since the pressure chamber defined by the

diaphragms 168 and 170 is communicated with the suction head of the engine, as long as this suction head is maintained at a sufficiently high level, a negative pressure will be acting upon the diaphragm 168. This negative pressure causes the diaphragm 168 to flex downwardly, moving the actuator rod 174 into engagement with the needle valve 176 to maintain the latter closed regardless of the pressure in the passage 120. Once the throttle valve 81 is again moved to an open position, the suction head of the engine decreases in magnitude, thereby relieving the negative pressure within the chamber between diaphragms 168 and 170 to allow the coil spring 180 to return the rod 174 to its raised position which, in turn, allows the coil spring 178 to return the needle valve 176 and the closure plate 186 to their open positions. It is to be understood of course, that the magnitude of the suction head of the engine is substantially greater when the engine is operating at a relatively high speed as the vehicle descends a long steep grade with the throttle valve 81 closed than is the case when the throttle valve is closed and the engine is operating at "curb" idle. The diaphragm 168 is selected to allow flexing thereof in response to the relatively great suction head which occurs when the engine is operating at a relatively high speed and when no fuel is required to be supplied thereto, but is of a size sufficient to preclude flexing under the influence of the relatively small suction head present during curb idle. Thus, the flow of fuel will not be cut off when it is required to keep the engine operating at idle speeds.

As the throttle valve 81 is opened, the arm 140 is raised, carrying with it the plunger mechanism 134 and creating a suction in the chamber 118 which draws fuel through the inlet 124 into the passage 120 to again fill the chamber 118 with fuel.

It is to be understood that the actuator rod 174 and its associated pressure chamber are not essential to the functioning of the needle valve 176 and can be deleted from the carburetor if desired. In such case, the valve 176 is opened and closed solely in response to flexing of the diaphragm 132 and the valve would not remain closed while the engine descended a long steep grade. With the actuator rod 174 positioned above the needle valve 176, as is preferred, the opening in the adjacent housing through which the actuator rod passes also provides a relief opening for fuel under excessive pressure within the passage 120. Any fuel passing through this relief passage is free to flow back into the storage area 110 through connecting passageway 182. It is also to be understood that while a double valve arrangement utilizing closure plate 186 and needle valve 176, is preferable from a design standpoint, a single closure valve could be utilized to block the conduit 152 and the bore 66 which branches therefrom.

It will be appreciated that the fuel shutoff control mechanism not only gives greater fuel economy and combustion efficiency but also eliminates the need for mechanical devices for maintaining the engine at an undesired increased speed while excess fuel is burned. The result is a much smoother transition of the engine to an idle speed.

Referring now to the alternative form of the invention illustrated in FIGS. 4 and 5, an upper boss 220 of generally rectangular cross section is utilized in cooperation with the lower boss 26 to mount the air motor 18 within the air horn presented by the housing 10. A suction conduit 192 extends upwardly toward the leading edge of the boss 220 to present an outlet port 194 into the air passage 212. The suction conduit 192 communicates with the fuel passage through bolt 38 and hollow axle 50 in the same manner as described in the preferred embodiment for the suction conduits presented by opening 96 and passages 102 and 104. An air director member in the nature of an annular body 196 of sharply decreasing cross-sectional dimension presents a boost venturi and is spaced from the outlet port 194 in surrounding relationship to the boss 220. A second annular body 198 also of sharply decreasing cross-sectional dimension, has an inside diameter greater than the outside diameter of the annular body 196 and is spaced downwardly from the latter with the edge of smallest

cross-sectional dimension of the body 196 being adjacent the area of greatest cross-sectional dimension of the body 198. It is to be understood that a second suction conduit, identical to the conduit 192, is disposed within the boss 220 at approximately 180° removed from the conduit 192, although this second conduit has been omitted from FIG. 4 for clarity. The outlet port 194' of the second suction conduit is, however, visible in FIG. 5.

Operation of the alternative form of the invention is identical to the operation of the preferred embodiment previously described. However, the presence of the venturi boost rings 196 and 198 creates an increased suction at the ports 194 and 194' as air flows through the passage 12. This increased suction draws fuel through the fuel passage and into the hollow, 10 rotatable hub 52 at an increased rate, thereby effectively utilizing the increased capacity of the carburetor.

Referring now to a further modification of the invention which is illustrated in FIGS. 6 and 7, an annular housing 310 presents an air horn which defines a central air passage 312 within which the air motor 18 is mounted by bosses 20 and 26, 20 the latter being supported by radially extending fins 24 and 28. The lower end of the housing 310 flares outwardly and is integral with the fin 28 to present a pair of adjacent air passages 200 and 202 disposed beneath the air motor 18.

Operation of the air motor 18 and the associated idle fuel shutoff control mechanism is the same with the embodiment illustrated in FIGS. 6 and 7 as for the other embodiments previously described. The air horn presented by passage 310 is, however, designed to be used with a typical V-6 or V-8 engine having a pair of cylinder banks, the passages 200 and 202 communicating directly with the respective cylinder banks. Although heretofore it has not been practical to deliver fuel to both barrels of a two-barrel carburetor from a single fuel metering and discharge system, because there was no assurance that there would be equal flow to each of the two barrels, this is now possible with the air motor 18 since the latter inherently gives an equal flow distribution to both barrels. It will be appreciated that the modified form of the invention illustrated in FIGS. 3 and 4 and described above has equal applicability to the two-barrel carburetor of FIGS. 6 and 7.

Having thus described the invention, what is claimed as new and desired to be secured by Letters Patent is:

1. In a carburetor for use with an internal combustion engine that creates a suction head during operation, said carburetor having an air horn and a rotatable air motor mounted within the air horn, the combination with said air motor of: turbine means coupled with said air motor for sustaining operation of the latter at an increased speed of rotation when the flow of air past the air motor is reduced; and means defining an air passage communicating with said turbine means and adapted to be communicated with said suction head to cause airflow over the turbine means to rotate the latter, whereby to effect rotation of said air motor at said increased speed.
2. The invention of claim 1, and means selectively positionable within said air passage for controlling the airflow over said turbine and hence the speed of rotation of the latter, whereby to control the speed of rotation of said air motor.
3. The invention of claim 1, said air horn being provided with a venturi constriction, said air motor having a hollow, rotatable hub, a plurality of vanes disposed around the hub, and fuel delivery means in communication with the hub; means defining a fuel passage in communication with said hub; and means defining a suction conduit in communication with said fuel passage and presenting an outlet port into the air horn at said venturi constriction, whereby the suction created by the passage of air through the air horn draws fuel through said fuel passage and into said hollow hub.
4. The invention of claim 3,

said turbine means including a second hollow, rotatable hub coaxial with the first-mentioned rotatable hub, spaced from the latter, and having a plurality of vanes disposed therearound, said suction conduit extending through said second rotatable hub.

5. The invention of claim 3, and structure mounting said air motor within the venturi constriction,

said structure and said air horn defining a second suction conduit in communication with said first suction conduit and presenting an outlet port into the air horn in opposed relationship to the first-mentioned suction conduit outlet port, whereby the suction drawing fuel through said fuel passage is the average suction at the first and second suction conduit outlet ports.

6. The invention of claim 3,

said suction conduit being disposed adjacent said air passage; and sealing means separating said suction conduit from said air passage.

7. The invention of claim 3, and

an air director member within the air horn spaced from said outlet port and presenting a boost venturi for drawing air from said outlet port and through said suction conduit whereby fuel is drawn through the fuel passage and into the hollow hub of the air motor as a result of the flow of air through said air horn and past said boost venturi.

8. The invention of claim 7,

said carburetor being adapted for use with an engine of the kind having a pair of cylinder banks, said carburetor having a pair of air passages communicating with the air horn and each adapted for communication with a corresponding cylinder bank.

9. The invention of claim 1,

said air motor and said turbine means having a common axis of rotation; and means intercoupling said air motor and said turbine means for rotation in unison in the same direction.

10. The invention of claim 1,

said air motor including an axle having an extension and a hub secured to the axle and provided with a plurality of vanes therearound, said turbine means being rigidly mounted on said extension.

11. The invention of claim 1,

said carburetor being adapted for use with an engine of the kind having a pair of cylinder banks, said carburetor having a pair of air passages communicating with the air horn and each adapted for communication with a corresponding cylinder bank.

12. In a carburetor:

an air horn provided with a venturi constriction; a rotatable air motor mounted within the horn and having a hollow hub; means defining a fuel passage in communication with said hub;

means defining a suction conduit in communication with said passage and having an outlet port into the horn; and an air director member within the horn spaced from said port and presenting a boost venturi for drawing air from said port and through said conduit, whereby fuel is drawn through the passage and into the hub as a result of the flow of air through said horn and past said boost venturi.

13. The invention of claim 12,

said member having a surface facing the port, said surface diverging from the port in the direction of airflow.

14. The invention of claim 13, and

a second annular body having a surface facing the port, said surface of the second body diverging from the port in the direction of airflow, said second body having an inside diameter greater than the outside diameter of the first-mentioned body,

said second body being spaced downwardly from the first-mentioned body with the edge of smallest cross-sectional dimension of the latter being adjacent the area of greatest cross-sectional dimension of the latter.

15. In a carburetor for an internal combustion engine that creates a suction head during operation, said carburetor including a fuel compartment, a throttle valve for controlling the flow of fuel from said compartment to the engine, and a conduit for delivering idle fuel from the compartment to the engine when said valve is in a closed position, the combination with said carburetor of idle fuel shutoff means comprising:

a chamber;
a passage interconnecting the chamber and the compartment for maintaining a supply of fuel in the chamber; mechanism operably coupled with said valve for forcing fuel from said chamber and into the passage in response to movement of the valve toward the closed position; structure in said passage yieldable to the pressure of fuel forced into the passage; and means responsive to the yielding of said structure for blocking the flow of fuel in said conduit from said compartment to the engine.

16. The invention of claim 15, wherein said structure comprises a diaphragm which presents a portion of said passage.

17. The invention of claim 16, wherein said responsive means comprises a valve coupled with said diaphragm; and yieldable means for biasing said valve into an open position.

18. The invention of claim 15, and first and second check valves within said passage, said first check valve being disposed to block the flow of fluid from the passage while allowing the flow of fuel into the latter from said compartment, said second check valve being disposed to present a restricted orifice by which fuel flowing through the passage from the chamber is discharged into said compartment.

19. The invention of claim 15, wherein said mechanism includes a plunger and an operating rod for actuating said plunger.

20. The invention of claim 19, wherein said plunger is provided with an upstanding stem, said operating rod is slidably received on said stem; and yieldable means acting against said operating rod to bias the latter away from the plunger.

21. The invention of claim 15, wherein the carburetor conduit is branched to present a fuel-conveying bore for delivering fuel to the engine, and said responsive means includes a first valve coupled with said structure for blocking the conduit below said bore, and a second valve coupled with said structure for blocking the conduit above said bore.

22. The invention of claim 21, wherein said first valve comprises a needle valve coupled with said structure, and said second valve comprises a closure plate mounted on said needle valve.

23. The invention of claim 22, and first yieldable means biasing said needle valve into an open position, said closure plate being slidably mounted on said needle valve; there being retainer means on said needle valve for limiting sliding movement of said closure plate in one direction; and second yieldable means biasing said closure plate against said retainer means.

24. The invention of claim 15, including a pressure responsive actuator for operating said responsive means independently of the yielding of said structure; and means defining an air passage communicating said actuator with the suction head of the engine whereby the actuator operates said responsive means to cause the latter to block the flow of fuel in the conduit in response to the decrease in pressure caused by the suction head of the engine.

25. The invention of claim 24, wherein said actuator includes a pressure chamber at least partially defined by a yieldable member, and an actuating rod coupled with said member, said air passage communicating with said pressure chamber.

26. In a carburetor for use with an internal combustion engine that creates a suction head during operation, said carburetor

retor having an air horn, a rotatable air motor mounted within the air horn, a fuel compartment, a throttle valve for controlling the flow of fuel from said compartment to the engine, and a conduit for delivering idle fuel from the compartment to the engine when said valve is in a closed position, the combination with said carburetor of:

turbine means coupled with said air motor for sustaining operation of the latter at an increased speed of rotation when the flow of air past the motor is reduced;

means defining an air passage communicating with said turbine means and adapted to be communicated with said suction head to cause airflow over the turbine means to rotate the latter;

a chamber;
a passage interconnecting the chamber and the compartment for maintaining a supply of fuel in the chamber; mechanism operably coupled with said valve for forcing fuel from said chamber and into the passage in response to movement of the valve toward the closed position;

structure in said passage yieldable to the pressure of fuel into the passage; and

means responsive to the yielding of said structure for blocking the flow of fuel in said conduit from said compartment to the engine.

27. The invention of claim 26, and
an air director member within the air horn spaced from said outlet port and presenting a boost venturi for drawing air from said outlet port and through said suction conduit whereby fuel is drawn through the fuel passage and into the hollow hub of the air motor as a result of the flow of air through said air horn and past said boost venturi.

28. In a carburetor for use with an internal combustion engine that creates a suction head during operation, said carburetor having an air horn, a rotatable air motor mounted within the air horn, a fuel compartment, a throttle valve for controlling the flow of fuel from said compartment to the engine, and a conduit for delivering idle fuel from the compartment to the engine when said valve is in a closed position, the combination with said carburetor of:

turbine means coupled with said air motor for sustaining operation of the latter at an increased speed of rotation when the flow of air past the motor is reduced;

pressure responsive means for blocking the flow of fuel in said conduit from said compartment to the engine; and
means defining an air passage communicating said pressure responsive means and said turbine means with said suction head to cause airflow over the turbine means to rotate the latter and said pressure responsive means to block the flow of fuel in said conduit in response to the decrease in pressure caused by the suction head.

29. The invention of claim 28,
said carburetor being adapted for use with an engine of the kind having a pair of cylinder banks,
said carburetor having a pair of air passages communicating with the air horn and each adapted for communication with a corresponding cylinder bank.

30. In a carburetor for use with an internal combustion engine that creates a suction head during operation, said carburetor having an air horn, a rotatable air motor mounted within the air horn, a fuel compartment, a throttle valve for controlling the flow of fuel from said compartment to the engine, and a conduit for delivering idle fuel from the compartment to the engine when said valve is in a closed position, the combination with said carburetor of:

turbine means coupled with said air motor for sustaining operation of the latter at an increased speed of rotation when the flow of air past the motor is reduced;

a chamber;
a passage interconnecting the chamber and the compartment for maintaining a supply of fuel in the chamber; mechanism operably coupled with said valve for forcing fuel from said chamber and into the passage in response to movement of the valve toward a closed position;

structure in said passage yieldable to the pressure of fuel forced into the passage;
 means responsive to the yielding of said structure for blocking the flow of fuel in said conduit from said compartment to the engine;
 a pressure responsive actuator for operating said responsive means independently of the yielding of said structure; and means defining an air passage communicating said actuator and said turbine means with said suction head whereby the actuator operates said responsive means to cause the latter to block the flow of fuel in the conduit and air flows over said turbine means to rotate the latter, both in response to the decrease in pressure caused by the suction head.

15

31. The invention of claim 30, said carburetor being adapted for use with an engine of the kind having a pair of cylinder banks, said carburetor having a pair of air passages communicating with the air horn and each adapted for communication with a corresponding cylinder bank.

32. The invention of claim 31, and

an air director member within the air horn spaced from said outlet port and presenting a boost venturi for drawing air from said outlet port and through said suction conduit whereby fuel is drawn through the fuel passage and into the hollow hub of the air motor as a result of the flow of air through said air horn and past said boost venturi.
